UNITED STATES PATENT OFFICE

ADAM A. BREUER, OF CHICAGO, ILLINOIS

SPRAYING DEVICE

Application filed February 16, 1928. Serial No. 254,715.

This invention relates to spraying devices in which the liquid to be applied is projected onto the object to be treated by a current of air.

5 Heretofore it has been customary to produce the desired current of air by a hand pump which has numerous disadvantages such as lack of throwing power, intermittency of operation and so forth.

10 Another disadvantage of the old types of spraying device was the readiness with which the liquid contents spilled.

15 It is an object of the present invention, therefore, to provide an improved spraying device as regards both air and liquid supply.

A further object of this invention is to provide a pressure sprayer in which spillage of the liquid contents is prevented in every position of use of the sprayer.

20 Other and further important objects of the invention will be apparent from the disclosures in the accompanying drawings and the following specification.

The invention (in a preferred form) is illustrated on the drawings and hereinafter more fully described.

On the drawings:

Figure 1 is a side elevation of one form of the device as a whole.

30 Figure 2 is a central vertical section through the liquid receptacles, nozzles, and parts integral therewith.

Figure 3 is a detail sectional view on the line III—III of Figure 2.

35 Figure 4 is a longitudinal central section through the liquid nozzle or jet.

Figure 5 is a detail view showing a modified form of construction.

As shown on the drawings:

40 The device comprises a tank 1 for the liquid to be sprayed, conveniently formed of sheet metal. Across the top and preferably soldered thereto is an air discharge pipe 2. This pipe is conical in form not only to produce a more concentrated blast of air at its discharge end but also to facilitate the connection of the pipe to the discharge orifice of a portable electric blower 3. This is accomplished by a connector 4 having at one end a conical portion adapted frictionally to

engage the interior of the large end of the conical air discharge pipe 2. The other end of the connector 4 is formed with the usual internally arranged coupling lugs adapted to engage similar but externally arranged lugs 55 on the discharge orifices 5 of the blower. The blower comprises the customary encased motor and fan and is provided with a handle 6 carrying the controlling switch 7.

The tank or liquid receptacle 1 is provided with a liquid discharge tube 8 which extends from the rear lower part of the tank diagonally forwardly and upwardly into the front or discharge end of the pipe 2. The forward end of the tube 8 is bent so that its axis is concentric with that of the pipe 2. A nozzle 9 is threaded onto the discharge end of the tube 8 and by adjustment may within certain limits control the spread of the spray discharge. A slot 10 is cut in the end of the nozzle for engagement with a screw driver to facilitate its removal or replacement by a nozzle of different bore to suit liquids of various viscosities and kinds.

75 While the air passing out through the pipe 2 produces a suction on the liquid within the pipe 8 it is desirable to aid this suction by air pressure on the surface of the liquid within the tank. For this purpose an aperture 11 is provided in the bottom of pipe 2 and 80 the top of tank 1. To take advantage not only of the static pressure in the pipe 2 but also of the kinetic pressure a deflector 12 is provided adjacent this aperture. Conveniently the aperture and deflector are formed 85 by making a U-shaped cut in the metal and bending upwards the metal lying within such cut.

90 It is frequently desirable to point the spraying device upwards almost vertically and with an air aperture arranged centrally or thereabouts this cannot be done when the tank is nearly full of liquid without liquid running out of the aperture. If the aperture is disposed towards the front of the tank then the liquid will spill out when the spraying device is pointed downwards. To prevent the liquid spilling in any position in which the discharge end of the pipe 2 is 95 pointed and with the lower or rear end of 100

the tube 8 submerged in the liquid a trough shaped member 13 is attached to the under side of the top of the tank 1 and extending toward the discharge end of the pipe 2. This trough shaped member is closed at its rear end but open at its front end and so provides a passage from the aperture 11 to the front of the tank and is closed at all points except at its front end.

- 10 The trough 13 is preferably of greater width than depth and has its bottom substantially parallel with the cover and is so arranged to normally discharge air above the liquid in the tank 1. Should the pipe 2 be 75
15 pointed downwardly, then the incoming air in the trough would prevent liquid passing out through the same and thereby prevent spillage.

In place of a trough shaped member a tube 20 14 may be used, as shown in Figure 5. In this case one-half of the tube may be arranged to project into the pipe 2 to act as a deflector.

If desired, the aperture 11 may be disposed 25 further to the rear of the tank than as shown in the drawings so that the spraying device may be tipped until directed vertically downwards without spilling liquid. In that case, however, the rear end of the tube 8 would be 30 uncovered so that the device would cease to spray. For ordinary purposes, therefore, it is sufficient to arrange the aperture 11 about the center of the tank.

A handle 15 may conveniently be provided, 35 as shown, for lifting the tank and aiding in the direction of the spray.

I am aware that many changes may be made and numerous details of construction 40 may be varied through a wide range without departing from the principles of this invention, and I therefore do not purpose limiting the patent granted herein, otherwise than necessitated by the prior art.

I claim as my invention:

- 45 1. A device of the kind set forth comprising a container for liquid, an air discharge pipe extending across the top thereof, a liquid discharge pipe extending diagonally from a point adjacent the bottom of the container into said air discharge pipe, an air admission trough against the under side of the top, and leading from the top and front of the container rearwardly toward the center of the container and communicating at 50 its rear end with the air discharge pipe, said trough having its rear end closed.

2. A device of the kind set forth comprising a container for liquid, an air discharge pipe extending across the top thereof, a liquid discharge pipe extending from the rear lower corner of the container forwardly and upwardly into the air discharge pipe, an air admission trough lying against the underside of the top and leading from the top and 65 front of the container rearwardly towards

the center of the container and communicating at its rear end with the air discharge pipe, said trough having its rear end closed, and a deflector extending into the air discharge pipe and adapted to aid in diverting 70 a part of the air flowing through the air discharge pipe into said trough.

3. A device of the kind set forth comprising a blower, a connector having means for releasably attaching one end to the air outlet of the blower and a conical tubular portion at the other end, a container for liquid, a conical air discharge pipe extending across the top thereof, the larger end of which is adapted for frictional engagement with the 75 conical portion of the coupling member, and a liquid discharge pipe extending from a point adjacent the bottom of the container into said air discharge pipe, a trough against the underside of the container top extending 80 in the same direction and underlying said air discharge pipe and having communication with said air discharge pipe at a point remote from the discharge end of said air pipe, said trough communicating with the 85 interior of said container at a point above the normal level of the liquid therein and adjacent the discharge end of said air discharge pipe, said trough having its rear end closed.

4. A pressure sprayer including a liquid tank, a top for said tank, an air discharge pipe secured to said top, an air trough underlying said top and extending in the same direction as said pipe and having its outer end open and its rear or inner end closed and disposed to discharge immediately underneath the top so as to discharge air in the same general direction as the flow of the air through said pipe, said top having an aperture therein between said pipe and said trough near the rear end of said trough for affording communication therebetween, a liquid discharge pipe supported by said top and having its discharge end within and adjacent the discharge end of said air discharge pipe and extending downwardly and diagonally rearwardly from its discharge end and terminating near the bottom and rear of said tank at a point remote from the discharge end, said liquid discharge pipe being substantially 95 straight for the greater portion of its length, and said trough being so arranged with respect to said air discharge pipe as to have the discharge end of the trough substantially 100 underneath the discharge end of the air discharge pipe.

In testimony whereof I have hereunto subscribed my name at Chicago, Cook County, Illinois.

ADAM A. BREUER. 121
